C. V. RAICEVICH

CASEMENT ADJUSTER FOR SWINGING SASHES OR SHUTTERS

Filed July 26, 1922

Patented Aug. 21, 1923.

1,465,315

UNITED STATES PATENT OFFICE.

CHRISTOPHER V. RAICEVICH, OF NEW ORLEANS, LOUISIANA.

CASEMENT ADJUSTER FOR SWINGING SASHES OR SHUTTERS.

Application filed July 26, 1922. Serial No. 577,575.

To all whom it may concern:

Be it known that I, CHRISTOPHER V. RAICEVICH, a citizen of the United States, residing at New Orleans, in the parish of Orleans and State of Louisiana, have invented certain new and useful Improvements in Casement Adjusters for Swinging Sashes or Shutters, of which the following is a specification.

- 10 My invention relates to improved means for opening and closing, and for adjusting the extent of opening, of a window casement of that type which swings outwards on hinges. With such casements it is desirable 15 to adjust the same to any desired position from the fully open to the fully closed, and to hold the same firmly in such position against the normal action of wind, rain or the like.
- 20 My invention comprises a certain novel arrangement and certain novel combinations of parts which will be hereinafter more fully described and claimed.

Reference is had to the accompanying 25 drawings, in which like parts are indicated by similar reference symbols throughout the several views, and in which:—

Figure 1 is a plan view, partly in section through the casement, showing the sash in 30 the closed position in full lines, and in the fully open position in dotted lines, part of the guide rail being broken away to show the head of the sliding pivot block.

Figure 2 is a detail view showing in perspective, and on a larger scale, the sliding pivot block which is connected to the sash.

Figure 3 is a detail showing in perspective the detachable head for the sliding block which engages in the guide rail.

40 Figure 4 is a top plan view of the sliding pivot block with the detachable head connected thereto, said head being shown in section.

Figure 5 shows a section along the line 45 5—5 of Fig. 1, and looking in the direction of the arrows, the parts being shown on a larger scale.

Figure 6 shows a section along the line 50 6—6 of Fig. 1, and looking in the direction of the arrows.

Figure 7 is an enlarged plan view of the operating handle, parts being broken away to show the rack above, which is mounted on the window sill.

Figure 8 shows a section along the line 55 8—8 of Fig. 6, and looking in the direction of the arrows; and

Figure 9 is a detail view showing the guide rail removed from the sash.

A represents the window frame, A' the window sill, B the window sash which is hinged to the frame, as at C, and swings outwards in the usual way, said sash being shown as provided with glass B'.

D represents the guide rail fast to the 65 lower edge of the sash and provided with a slot d in the inner side thereof to permit the travel of the sliding pivot block E. This pivot block is preferably provided with a lug e, provided with a pinhole e', and with 70 a lug e² provided with a tenon e³, which lugs project, respectively, into the slots f and f' of an adjustable head F which is preferably formed of a sheet of resilient metal, having its ends bent, as shown at f², f³ and f⁴, to 75 form a light hollow guide head for the sliding pivot block. This guide head slides in the guideway of the guide rail D. Owing to its hollow resilient construction, this guide head is not apt to become jammed in the 80 guide rail no matter what may be the position of the sash. The lug e fits snugly in the slot f, and the lug e² passes up through the elongated slot f', the parts when connected together being in the position shown 85 in Fig. 4.

Below the head F the sliding pivot block is provided with a guide rib e⁴ which slides in the slot d of the guide rail. This block E is also provided with outwardly projecting lugs e⁵, perforated as at e⁶ to receive the pivot pin E' to which the arm H' of the operating handle H is pivotally connected. This operating handle is provided with a hand lever H², and is pivoted on the central 90 stud I' of the rack I, which is secured to the window sill A' in any convenient way, as by means of the flange I² and the bolts J, see 95 Figs. 1 and 7.

The operating handle is provided with 100 an enlarged central portion or casing H³ surrounding the pivot I', and this portion is provided with a downwardly projecting arcuate rib h, adapted to engage the guide groove i outside of the rack I³, see Fig. 6. 105 This rack is in the form of an arc of a circle, as shown in Fig. 7, concentric with the pivot stud I'. This pivot stud is preferably re-

duced at its upper end i^2 to engage the metal strap K, shown most clearly in Figs. 5 and 7, which strap has its ends k secured to the window sill as by means of the bolts L. 5 This strap prevents the handle from being accidentally removed from the rack bar.

The arm H^2 of the handle is provided with a guide groove h^2 to receive the pawl M, which may be either gravity operated or 10 spring operated. This pawl is shown in Fig. 6 as gravity operated, and is hinged to the arm H^2 , as at m, and has its free end provided with a tooth m' adapted to engage the teeth of the rack I ^{3} . This pawl may be 15 disengaged, when it is desired to turn the handle about its pivot, by simply pressing up on said pawl, and when the pawl is released it will fall by its own weight into engagement with the rack teeth, as shown in 20 Fig. 6. If a positive lock is desired, a spring impressed pawl may be used, such as are well known in the art.

In order to limit the angle through which the handle may be rotated, I may provide 25 a lug h^0 projecting downwardly into the casing H^3 , as shown in Figs. 6 and 7, which lug engages stop lugs i^3 and i^4 , projecting from the pivot stud I' of the rack block I, as shown in dotted lines in Fig. 7.

30 The operation of the device is as follows: The sash being in the closed position shown in full lines in Fig. 1, if it is desired to open same grasp the arm H^2 with the hand, in so doing the pawl M will be lifted 35 from engagement with the rack, and the sash may be swung outwards by swinging the arm H^2 to the right of Fig. 1. If the sash sticks, pressure outwards may be applied to the same with the right hand, using the 40 left hand to swing the arm H^2 . As the sash swings outwards, the sliding pivot block E will draw the head F to the left in the guide rail D and when the sash is fully open the parts will be in the position as indicated in 45 dotted lines in Fig. 1.

The sash may be moved to the fully open or any intermediate open position, and will be automatically locked when the pawl M is released. Obviously the parts sliding in 50 the guide rail D should be suitably lubricated.

The resilient loops of the sliding head F will not only prevent those parts from jamming, but will also in a large measure obviate rattling due to variations in wind pressure. 55

It will be noted that the device hereinbefore described may be applied to any swinging easement, whether a window sash, shutter, blind, or the like, without requiring structural changes in such of those parts of

the building as they are ordinarily constructed.

The device may be applied to the swinging sash of a shutter, and to the window sill by 6 the use of simple tools and may be conveniently taken off when its use is no longer desired. Thus, for instance, the device may be applied in the summer and taken off when cold weather comes, or it may be left permanently attached to the window as desired. 7

It will be obvious that various modifications might be made in the herein described construction, and in the combination and arrangement of parts which could 7 be used without departing from the spirit of my invention; and I do not mean to limit the invention to such details except as particularly pointed out in the claims.

Having thus described my invention, what I claim and desire to secure by Letters Patent of the United States is:—

1. An attachment for adjusting swinging sashes, shutters or the like in the desired position comprising a hollow guide rail secured to the swinging sash, a pivot block slidably connected to said guide rail said pivot block including a body portion and a detachable head made of a strip or resilient bent metal adapted to engage in said track rail, a segmental rack secured to the window or door frame and provided with a central pivot, an operating bar having one end pivoted to the body portion of said pivot block and the other end terminating in a handle, the said operating bar being pivoted above said rack, and a pawl pivoted to said handle and normally engaging said rack, but adapted to be withdrawn from such engagement when said handle is gripped by the operator.

2. An attachment for adjusting swinging sashes, shutters or the like in the desired position comprising a hollow guide rail secured to the swinging sash, a pivot block 1 slidably connected to said guide rail said pivot block including a body portion and a detachable head made of a strip of resilient bent metal adapted to engage in said track rail, a segmental rack secured to the window 1 or door frame and provided with a central pivot, an operating bar having one end pivoted to the body portion of said pivot block and the other end terminating in a hollow handle, the said operating bar being pivoted above said rack, and a pawl pivoted in the hollow portion of said handle and normally engaging said rack, but adapted to be withdrawn from such engagement when said handle is gripped by the operator.
